UNITED STATES PATENT OFFICE.

GEORGE R. BUFFHAM, OF BALTIMORE, MARYLAND.

DESIGN FOR AN ORNAMENTAL STAND.

SPECIFICATION forming part of Design No. 20,425, dated December 23, 1890.

Application filed October 10, 1890. Serial No. 367,730. Term of patent 3½ years.

To all whom it may concern:

Be it known that I, GEORGE R. BUFFHAM, a citizen of the United States, residing at Baltimore, in the State of Maryland, have invented and produced a new and original Design for Ornamental Stands, of which the following is a specification.

In the drawing herewith the figure is a perspective view of my design applied to a stand having a three-cornered base.

The design is an ornament for small stands for use on the center-table, the mantel, or the dressing-bureau; and it consists of a stand-base A of any desired form surmounted by a quinary-pronged body B, the said five-pronged body having a breadth about equal to or approximating that of the stand-base, so that when viewed in elevation there will be somewhat of a correspondence in size between the said base and body, and thus give the latter a bold effect. The base has ornamented

raised work c of fanciful figures on its front face, which may vary in character, and the body B, with its five radiating prongs d, rests upon or projects up above the base. The prongs 25 taper and are somewhat irregular or slightly curved in their contour. The five-pronged or star-shaped body has a small hook e and a ribbon bow attached.

I claim—

The design for small stands herein shown and described, consisting of the stand-base A, surmounted by a body B, having five radiating prongs, said body and prongs having a breadth about equal or approximating that 35 of the stand-base.

In testimony whereof I affix my signature in the presence of two witnesses.

GEORGE R. BUFFHAM.
